UNITED STATES PATENT OFFICE

2,508,374

HAIR CURLER

Joseph S. Cipolla, Brooklyn, N. Y.

Application March 13, 1948, Serial No. 14,725

1 Claim. (Cl. 132—40)

1

The present invention relates to new and improved methods of imparting permanent waves to hair on the human head and to new and improved means for performing said methods.

Objects and advantages of the invention will be set forth in part hereinafter and in part will be obvious herefrom; or may be learned by practice with the invention, the same being realized and attained by means of the instrumentalities and combinations pointed out in the appended claim.

The invention consists in the novel parts, constructions, arrangements, combinations and improvements herein shown and described.

The accompanying drawings, referred to herein and constituting a part hereof, illustrate a preferred embodiment of the invention, and together with the description, serve to explain the principles of the invention.

A primary object of this invention is to provide a method and means for permanently waving hair which will eliminate the so called setting operation, after the waving operation, which is necessary in virtually all permanent waving systems heretofore known.

In all permanent waving systems now used whether the wave is imparted by means of electric resistance heat, heat from an exothermic chemical reaction, or by so-called cold waving imparted by a chemical treatment of the hair without the use of heat, after the wave is imparted, each waved tress must be removed from the curler around which it is wrapped, and then re-set or styled into the form in which it is to be worn. This involves setting the tresses into different formations than those in which the wave was given.

By use of the present invention this series of steps is eliminated so that when the curls are formed and processed the desired curls and styling are formed and determined in one operation. Thereby the setting operation ordinarily necessary is eliminated.

Of the drawings:

Figure 1 is a view in perspective of an embodiment of the present invention comprising a relatively rigid spindle attached to a slotted base.

Figure 2 is a view in vertical section taken along the line 2—2 of Figure 1.

Figure 3 is a view in perspective of the device of the claim showing the start of a curling or winding operation of a tress of hair.

Figure 4 is a view of the device of the claim with the winding operation started in Figure 3 completed.

Fig. 5 is a view similar to Fig. 2 of an alternative embodiment of the present invention.

Generally in using the devices of this invention in permanent waving a tress of hair is wound upon a spindle which is preferably in fixed journalized relation to a base or disc member which is resilient and slotted. After being wound in coiled form on the spindle almost to the scalp, the proximal portion of the tress is passed through the slotted portion of the disc and the spindle bearing the coil of hair is then rotated with respect to the disc tensioning the tress and forcing the disc against the scalp.

Referring now in detail to the accompanying drawings, Figure 1 shows a spindle 1 having a longitudinal slot 2. Said spindle is journaled in a disc 3, having a slot 4 terminating in an enlarged inner portion 5.

Preferably the spindle 1 is formed of a relatively rigid material such as a thermosetting resin while the disc 3 is made of a flexible resilient material such as rubber. The spindle, in the embodiment of Figures 1 and 2, has near one end thereof a pair of flanges 7 and 8. The distance between said flanges is less than the normal thickness of the disc 3 so that when said disc is attached to said spindle 1, the portion of the disc positioned between said flanges 7 and 8 will be compressibly retained. Such a structural relationship will maintain the spindle and disc in normally fixed relation, yet will permit relative movement under cooperative frictional restraint.

Flange 7 is preferably beveled off so that when the disc 3 is in contact with it and flange 8 the periphery of the flange 7 and the adjacent surface of disc 3 will provide an uninterrupted surface so that when a tress of hair is wound on the device it will be difficult for any random strands of hair to be caught between the flange 7 and the disc thereby tending to result in a more perfect wave and eliminate a possible source of discomfort to the recipient of the wave. To further this purpose, flange 8 is preferably of a smaller diameter than flange 7. Additionally such disparity between the diameters of said flanges will facilitate assembly of the spindle-disc structure.

Figure 3 shows the distal end 11 of a tress of hair 10 placed in the slot 2 of spindle 1 in the initial step of the winding operation.

The tress is then wound on the spindle toward the proximal end of the tress until the device is quite near the scalp. The proximal portion of said tress 10 is then passed through the slot 4 to its enlarged inner portion 5. The disc is then

held against movement and close to the scalp while the spindle 1 is further rotated with respect to the disc so that the remainder of the tress 10 is wound and tensioned on said spindle, forcing said disc 3 against the scalp, as shown in Figure 4, where it is retained until the waving action is completed.

Figure 5 is an alternative embodiment of the invention showing a spindle 15 adapted to rotate about a flanged bolt 16 which is attached to a disc member 17, by a nut 18.

Said bolt 16 when tightened with respect to said nut compresses said spindle 15 in frictional bearing relationship against said base member 17. Said spindle has a flange member 20, and the base member 17 has a slot 21 terminating in an inner enlarged portion 22, which are equivalent to the respective portions flange 7 and slot 4 and inner portion 5 of Figures 1 and 2.

The devices and methods of this invention are particularly adapted for use in the cold permanent waving methods which customarily are given in the form of Croquignole waves with the customary waving and neutralizing lotions known in the art. In such cold waving this invention has an additional advantage that after the waving lotion has acted on the tress under tension the spindle can be somewhat loosened to relax the hair during the neutralizing step to facilitate complete penetration of the tress, particularly that portion closest to the spindle. The tress can again be re-tensioned if desired. The waving solution may be applied to the tress before winding, as in so-called wet winding, or after the winding is completed.

Such control of the tension of the curl on the spindle permits accurate control of the tightness of the curl ultimately imparted. Therefore, a head of hair may be waved in a predetermined pattern, with the elimination of the usual guess-work about the outcome. Consequently as one style is sketched or otherwise indicated by a hair stylist, the wave may be competently given by a relatively inexpert operator.

When the devices of the invention are used in exothermic machineless waving it is necessary,

of course to provide a protective insulating sheet, as of felt or the like, between the curler and the scalp to protect the scalp from steam or condensate from the chemical reaction of the machineless waving pads.

Naturally, in this type of waving, the spindle would not be made of plastic material but preferably a metal such as a light aluminum alloy.

Other means than those illustrated and described of providing the operating relationship between the spindle and the base member of normally fixed but relatively rotatable connection will be apparent to those skilled in the art.

The invention in its broader aspects is not limited to the specific mechanisms shown and described but departures may be made therefrom within the scope of the accompanying claim without departing from the principles of the invention and without sacrificing its chief advantage.

What is claimed is:

A device for winding a tress of hair preparatory to permanently waving the same, said device comprising a flexible resilient disc having a through opening and a slot which extends inwardly from the periphery of the disc, and an elongated slender rigid spindle consisting solely of a rod-like member having its lower end frictionally received in the opening in the disc and having a pair of flanges frictionally engaging opposite faces of said disc whereby said disc and spindle normally will rotate together and said spindle can be rotated relatively to said disc under frictional restraint, said spindle having a slot for engaging and retaining an end of a tress.
